PAGE 2

Fig. 3

Fig. 4

Fig. 5Fig. 6

FIGURE 1 is a perspective view of a computer cabinet showing my new design;

FIGURE 2 is a front elevational view;

FIGURE 3 is a rear elevational view;

FIGURE 4 is a top plan view;

FIGURE 5 is a side elevational view; and

FIGURE 6 is a side elevational view of the opposite side thereof.

The dominant features of my design reside in the portion shown in solid lines.

I claim:

The ornamental design for a computer cabinet, substantially as shown and described.
